Elijah Skinner and John Webster
Gentlemen Patents.

The Defendants do hereby claim this Patent and make part of
the same containing a description in the words of the said Elijah Skinner
and John Webster themselves of their Improvement in Composition for
Painting called the "Stone Composition".

To all to whom the present shall come. Be it known that we Elijah
Skinner & John Webster of Sandwich in the County of Essex & State of
New Hampshire have invented a new & useful composition for painting
called the "Stone Composition" & that the following is a full & exact description
of the composition & use of said composition as invented or improved
by us. This composition is prepared by taking common fine stone or
stone well ground & broken & common white lead in equal quantities
which when well mixed together may be ground in either the ordinary
manner of grinding oil painted with the usual and necessary coloring. We
also contemplate painting such using said stone with other kinds of paints
of different colors whether with or without oil than such proportions as may
be necessary, or using said stone alone for the purpose of painting. But we
consider the use of said stone of the most convenience in paint that is de-
signed to be exposed to the weather, especially in white lead. What we
claim as new is the introduction of this particular species of stone into the
composition composition of paints. Sandwich, N. H. April 27, 1833
